UNITED STATES PATENT OFFICE.

GEORGE F. BULEN, OF JERSEY CITY, NEW JERSEY, ASSIGNOR TO THE AUTOMATIC FIRE ALARM AND EXTINGUISHER COMPANY, (LIMITED,) OF NEW YORK, N. Y.

THERMOSTATIC CIRCUIT-CLOSER.

SPECIFICATION forming part of Letters Patent No. 333,443, dated December 29, 1885.

Application filed June 14, 1882. Serial No. 64,144. (Model.)

To all whom it may concern:

Be it known that I, GEORGE F. BULEN, a citizen of the United States, and a resident of Jersey City, in the county of Hudson and State of New Jersey, have invented a new and useful Improvement in Thermostatic Circuit-Closers, of which the following is a specification.

The object of my invention is to provide a thermostat which will be readily affected by slight changes of temperature, and will by its expansion complete an electric circuit under the influence of any predetermined degree of heat, and to construct the same in a manner adapted to secure uniformity of action and freedom from the injurious effects due to the continually-recurring expansion and contraction of the metals of which it is composed.

My invention consists in supporting a thermostatic strip in a novel manner upon a peculiar form of base-plate, and in providing convenient means for covering the same, securing electrical connections therewith, and for supporting a contact-point for completing a circuit by the action of the thermostatic strip.

In the accompanying drawings, Figure 1 is a plan view of the exterior of a thermostat embodying my improvements. Fig. 2 is a cross-section of the same; and Fig. 3 is a plan showing the working parts of the apparatus, with the top or cover removed.

Referring to these figures, A represents a metallic base for supporting the various parts of the instrument.

Two binding-screws, a and a', are mounted on opposite sides of the instrument, for convenience in attaching electric conductors thereto. The binding-post a is in electrical connection with the metallic base A, while the post a' is insulated therefrom by means of suitable washers, b b, of hard rubber, porcelain, or other suitable material.

The thermostatic coil consists of two flat pieces of metal, c and c', (see Figs. 2 and 3,) having different coefficients of expansion securely brazed together and formed into an involute curve. The strip of metal c, upon the inner side of the curve, is preferably of iron, while the outer strip, c', is of brass or other

material having a coefficient of expansion about twice that of the inner strip, and is also double the thickness of the strip c. The inner end of the compound strip, which is situated at the origin c' of the spiral is supported from the base A, by means of a screw, D, extending through a metallic collar, d, into an aperture, d', in one side of which the end c' is secured by brazing, soldering, or otherwise. The outer or free end of the curved strip is provided with a contact-point, e', preferably faced with platinum to prevent corrosion. At a point beyond the normal position of this contact-point and directly in the line of the extended curve is supported a contact-stop, against which the point e' impinges, as hereinafter explained, when the thermostat is influenced by a sufficient increase of temperature. This contact-stop consists of a platinum point, e, supported upon an adjustable screw, E, which is mounted in a post, E. The post E is insulated from the base A in the same manner as has already been described with reference to the binding-post a', to which binding-post it is united by a suitable conducting-strip, e'. The contact-points e and e' are normally separated a short distance from each other, and this distance may be accurately adjusted by means of the movable screw E.

When for any reason the temperature in the building or room containing the thermostat increases or diminishes, the metals composing the section-strips c and c' expand or contract accordingly, but in different ratios, and the ratio of expansion of the outer strip being greater than that of the inner, the point e will be advanced toward the contact-point e' under the influence of an increase of temperature, and will be in like manner withdrawn when the temperature is decreased. It is evident, therefore, that the position of the contact-point e' may be so adjusted that the circuit will be completed between the points e and e' under the influence of any predetermined degree of heat, and hence by including the two points in an electric circuit containing a signaling apparatus an alarm may be automatically actuated thereby in a well-known manner. The terminal wires of such a circuit are shown at

W W in Fig. 1, and the apparatus may be united directly therewith at the binding-screws *a* and *a'*, or through the medium of short connecting-wires *w w*.

5 Over the top of the instrument and inclosing the thermostatic coil is fitted a cap or cover, *H*, of thin metal or other suitable material. This cover is preferably convex in shape, and has recesses formed in its edges, 10 as shown, which fit over the lateral lugs supporting the binding-posts *a* and *a'*. The cover is of spun metal, and is preferably secured in position by being fitted tightly over the edge or rim of the base *A*, but it may be secured 15 by screws or other suitable means.

For the purpose of protecting the instrument, when necessary, from moisture or dust, I provide an outer protector or shield, *G*, which is supported from the base *A* by means of a 20 screw, *g*, which screw is preferably provided with a shoulder, *g'*, to prevent the shield *G* from coming into contact with the two binding screws *a* and *a'*, and thereby short-circuiting the thermostat.

25 I claim as my invention--

1. In a thermostat, the combination, substantially as hereinbefore set forth, of a thermostatic strip, a metallic plate for supporting the same, a collar having an aperture in which 30 said strip is brazed or soldered, a screw extending through said collar into said base and uniting said strip and collar thereto, and an insulated contact-point applied to the remaining end of said strip.

2. The combination, substantially as hereinbefore set forth, of a thermostatic strip, a metallic base for supporting the same, an insulated screw carried upon said base, an adjustable contact-screw extending through a longitudinal opening in said insulated screw 40 into proximity to the end of said strip, and a convex spun-metal cover fitting over said strip and contact-point.

3. The combination, substantially as hereinbefore set forth, of a thermostatic strip, a metallic base-plate, an insulated screw supported upon the same having a horizontal opening through the same, a contact pin or screw extending through said opening, means for connecting one end of the strip to said 50 base, and a cover, *H*, for said strip.

4. The combination, substantially as hereinbefore set forth, of a thermostatic strip, the metallic base *A*, having lateral lugs, the screws *a* and *a'*, respectively supported upon said 55 lugs, one of which screws is insulated from said base, and a cover, *H*, for said strip, having recesses formed in its edges for receiving said lugs.

In testimony whereof I have hereunto subscribed my name this 9th day of June, A. D. 1882.

GEORGE F. BULEX.
